United States Patent Office.

ADOLPH PFAFF, OF BALTIMORE, MARYLAND.

Letters Patent No. 104,878, dated June 28, 1870.

IMPROVED MACHINE FOR CUTTING FAT, &c.

The Schedule referred to in these Letters Patent and making part of the same.

To all whom it may concern:

Be it known that I, ADOLPH PFAFF, of the city and county of Baltimore, in the State of Maryland, have invented a new and useful Machine for Cutting Fat, &c.; and I do hereby declare that the following is a full, clear, and exact description thereof, sufficient to enable those skilled in the art to which my invention appertains to make and use the same, reference being had to the accompanying drawing making part of this specification, in which—

Figure 1 is a central vertical section.

Figure 2 is a top view.

Figure 3 is an end view.

The nature of my invention consists in a peculiar arrangement and operation of devices for cutting fat, &c., first into slices, then into strips, and finally into squares or cubes, and delivering them into a receptacle prepared for them.

In a box or casing, A, made of any suitable form and dimensions, and of any suitable material, a shaft, B, is journaled, and attached to this shaft is a series of circular knives, C.

At a suitable distance from, and parallel with, the shaft B, is another shaft, D, provided with a cylinder, E, having on its face a set of grooves, e, at distances corresponding with the distance apart of the knives C, and so placed that the knives enter the grooves as they revolve toward each other, as indicated by the arrows.

Just below the shafts B and D are two shafts, H and K, placed at right angles with those above them.

On the shaft H is a series of knives, I, arranged like those above described, and on the shaft K is a cylinder, J, having grooves j formed on its face, and the knives I and grooved cylinder J engage with each other in the manner above described.

The bearings for the journals of the shafts B, D, H, and K are elongated, as shown at l in fig. 1, so that when the knives and cylinders become worn, they may be adjusted nearer to each other.

The cylinders E and J may be made of wood or metal, as desired.

They are provided with small pins or projections p, to assist in carrying down the fat, &c., as they revolve.

The knives C are provided with a cleaning device, M, consisting of a piece of wood or metal, with slits

formed in it, and placed so as to clean the knives as they revolve, after cutting the fat, &c.

Below the shafts H and K is a tube or trough, O, the inner end of which is near the point of contact of the knives I and cylinder J. From thence the trough is curved downward and outward, and terminates at one end or side of the box or casing A.

The upper side of the trough O is formed with slits which serve to clean the knives I.

On a shaft, R, which may be the main or driving-shaft, is a knife, S, attached at its center, so as to form two curved blades, as shown in fig. 3, and arranged so as to pass the outer end of the trough O at every revolution.

A cleaning device is also provided for this knife, and may consist of a piece of wood or metal, with a slit formed in it, placed so that the blades will pass through the slit at every revolution.

The shafts B, D, H, K, and O are connected by suitable spur-and-bevel gearing, so as to operate simultaneously.

The operation is as follows:

The fat, &c., is fed into the hopper V, where it is carried down by the cylinder E, and is cut into slices by the knives C. The slices then fall upon the cylinder J, and the knives I cut them at right angles, forming strips. The strips then pass into the trough O, and, as they are forced out at its end, they are cut into squares or cubes by the knife S, and fall into a suitable receptacle prepared for them.

What I claim as new, and desire to secure by Letters Patent, is—

1. The series of revolving knives C and revolving block E, with projecting points p and grooves e, in combination with shafts B and D, frame A, and crank R, constructed and arranged as shown and described.

2. The series of knives I, in combination with cutting-block J and j, with its cleaner M, as shown and described.

3. In combination with the above, the revolving S-formed knife S, the conducting-trough O, in combination with the devices for imparting motion, all as shown and described.
